UNITED STATES PATENT OFFICE.

ERIC S. KINTSEL, OF RATON, NEW MEXICO.

PENCIL-HOLDER.

1,327,762.

Specification of Letters Patent. Patented Jan. 13, 1920.

Application filed February 13, 1919. Serial No. 276,805.

To all whom it may concern:

Be it known that I, ERIC S. KINTSEL, a citizen of the United States, residing at Raton, in the county of Colfax and State of New Mexico, have invented certain new and useful Improvements in Pencil-Holders; and I do declare the following to be a full, clear, and exact description of the invention, such as will enable others skilled in the art to 10 which it appertains to make and use the same.

This invention relates to pencil holders, and it relates more specifically to an improved point-protecting holder for lead pencils.

One object of the invention is to provide an improved pencil holder that perfectly protects the point of the pencil held thereby.

Another object is to provide a pencil holder of this character which is adjustable to hold pencils of different lengths in the most convenient and desirable position relative to the hand of the user.

Another object is to provide an improved pencil holder which is very light, consistent with ample strength and durability.

Other objects and advantages may become apparent to persons who read the following details of description in connection with the accompanying drawings, in which:

Figure 1 is a side elevation of my improved pencil holder.

Fig. 2 is a front elevation.

Fig. 3 is a vertical sectional view in connection with a pencil held thereby.

Fig. 4 is a top plan view.

Fig. 5 is a transverse horizontal sectional view along the line 5—5 of Fig. 1.

Referring to these drawings in detail, in which similar reference characters correspond with similar parts throughout the several views, the device consists of a frame 7, a pair of spring clamping jaws 8, an adjustable point-protecting element 9 and an attaching element 10, the latter comprising a pin-fastener or safety pin which is secured to one end of the frame 7.

The frame 7 comprises a supporting and adjusting bar 11, a base plate 12, and a ring 13. The base plate 12 may be in the form of a disk, as shown in Figs. 1 and 5, and this plate extends laterally from one end of the bar 11, while the ring 13 extends parallel and substantially coextensive with the plate 12 from the other end of the bar 11. The

spring rods or clamping jaws 8 each have one end affixed to the plate 12, and the other ends of these clamping jaws extend through the ring 13 so that the latter limits the outward movement of their free ends and acts 60 as a shield or guard to protect these clamping jaws from being broken by their engagement with external objects.

The point-protecting element 9 comprises a tubular member, as more clearly shown in Figs. 3, 4 and 5, and is provided with a constricted portion 14 which engages the tapering portion of a pencil between the outwardly extending lead portion thereof and the major part of the pencil. This element 9 also comprises an enlarged cavity 15 below the constricted portion 14, and this cavity receives and guards the outwardly extending part of the lead or marking composition of the pencil. The member 14 also 70 comprises a funnel shaped or upwardly converging portion 16 which guides the pencil point into the constricted portion 14. An apertured lug 17 extends radially from the tubular member 9 and carries a set-screw 18 80 which engages with the bar 11 to hold the element 9 in different adjusted positions, it being understood that the bar 11 extends through an aperture of the lug 17, and that the screw 18 engages with the bar 11 for retaining the element 9 in its different adjustments relative to the frame 7.

In using this device, it may be pinned to the user's clothing by means of the pin 10, and the major part of the device may be enclosed within a pocket of the user. When a new or relatively long pencil is held by the device, as shown in Fig. 3, the protecting element 9 may be located adjacent to the plate 12. However, when the pencil has 90 been worn and trimmed until it becomes a mere stub, the screw 18 may be loosened, and the same may be employed as a handle for shifting the protecting element 9 along the rod 11. It will be seen that the clamping 100 jaws 8 press the pencil inward against the upper part of the bar 11 and coat therewith to prevent accidental movement of the pencil with relation to the holder. However, this frictional engagement of the clamping jaws 105 and bar 11 does not preclude the easy engagement and disengagement of the pencil with the holder.

It will be seen that this device may be constructed of steel or other relatively strong 110

and springy material, and that it may be very light consistent with the desirable strength, rigidity and durability.

Although I have described this embodiment 5 of my invention very specifically, it is not intended to limit this invention to these exact details of construction and arrangement of parts, but I am entitled to make changes within the scope of the inventive idea 10 disclosed in the foregoing description and following claims.

What I claim as my invention is:

1. A point-protecting pencil holder comprising a relatively long and narrow frame 15 formed with a ring at one end and with a guide element extending from the ring to the other end of the frame, a pencil engaging jaw secured to said other end of the frame and extending therefrom through said 20 ring, a tubular element formed with a constricted interior surface of a size and shape to fit around the converging part of a pencil inwardly of its projecting lead part and to leave a clear space around the latter,

means movably securing said tubular element to said guide element for adjustment along the latter to compensate for varying lengths of pencils to be held thereby, and means to attach said frame to a support. 25

2. A point-protecting pencil holder comprising a supporting and guiding bar having substantially co-extensive lateral extensions at its ends, one of said extensions being formed with an opening of a size larger than necessary to receive an ordinary lead pencil therethrough, a plurality of pencil-engaging spring jaws each having one end affixed to the other one of said lateral extensions and extending therefrom through said opening, means adjustable along said bar for protecting the outwardly extending lead portion of a pencil while engaging with the tapering part of the pencil inwardly of the said lead portion, and means to attach 30 said frame to a support. 35

In testimony whereof I have hereunto set my hand.

ERIC S. KINTSEL.
